Application February 23, 1938, Serial No. 191,856
In Germany February 24, 1937

14 Claims. (Cl. 62—119.5)

This invention relates to refrigeration and more particularly to a refrigeration system employing evaporation of refrigerant fluid in the presence of an inert gas or auxiliary agent.

It is an object of the invention to provide an improvement in systems of this type adapted to produce refrigeration at a plurality of temperatures.

This is accomplished by providing a plurality of places of evaporation for series flow of inert gas and in which liquid refrigerant evaporates, and flowing inert gas from a place of evaporation in heat exchange relation with inert gas flowing to such place of evaporation before the inert gas is conducted to another place of evaporation. With this arrangement, the mean temperature of one place of evaporation is lowered and the mean temperature differential between such place of evaporation and another place of evaporation is increased.

The invention, together with the above and other objects and advantages thereof, will be more fully understood upon reference to the following description and accompanying drawings forming a part of this specification and of which

Fig. 1 illustrates more or less diagrammatically a refrigeration system embodying the invention;

Fig. 2 is a view diagrammatically illustrating another manner of carrying out the invention shown in Fig. 1;

Fig. 3 is a fragmentary rear elevation of a refrigerator cabinet in which parts of the refrigeration system shown in Fig. 2 are mounted;

Fig. 4 is a vertical sectional view of the refrigerator shown in Fig. 3 and taken at lines 4—4 of Figs. 5 and 6;

Fig. 5 is a vertical sectional view taken at line 5—5 of Fig. 4; and

Fig. 6 is a horizontal sectional view taken at line 6—6 of Fig. 5.

Referring to Fig. 1, the invention is embodied in a refrigeration system of a uniform pressure type, generally as described in Patent No. 1,837,767 to Thore M. Elfving, in which an auxiliary pressure equalizing gas is employed. In a system of this type a refrigerant fluid, such as liquid ammonia, for example, may be introduced through conduits 10 and 11 into a cooling unit 12 which is arranged in a thermally insulated storage space 13. The refrigerant fluid evaporates and diffuses in cooling unit 12 into an inert gas, such as hydrogen, for example, to produce a refrigerating effect. The resulting rich gas mixture of refrigerant and inert gas flows from

cooling unit 12 through an outer passage 14 of gas heat exchanger 15 and vertical conduit 16 into the lower end of an absorber 17. The absorber 17 is diagrammatically shown in the form of a looped coil provided with a plurality of cooling fins 18.

In absorber 17 refrigerant vapor is absorbed by a suitable absorbent, such as water, which enters through a conduit 19. The hydrogen or inert gas, which is practically insoluble and weak in refrigerant, is returned to the upper part of cooling unit 12 through an inner passage 20 of the gas heat exchanger and conduit 21; and the enriched absorption liquid flows into an accumulation vessel 22. From vessel 22 enriched liquid flows through a conduit 23, an outer passage of liquid heat exchanger 24, and conduit 25 into rear chamber 26 of a generator 27.

By heating generator 27, as by a gas burner 28, for example, liquid is raised by vapor-lift action from chamber 26 through conduit 29 into the upper part of a stand-pipe 30. The liberated refrigerant vapor entering stand-pipe 30 through conduit 29, and also refrigerant vapor expelled from solution in stand-pipe 30 and chamber 31, flows upward through an air-cooled rectifier 32 into an air-cooled condenser 33 provided with a plurality of cooling fins 34. Refrigerant vapor is liquefied in condenser 33 and returned to cooling unit 12 through conduits 11 and 12, as will be described hereinafter, to complete the refrigerating cycle.

The weakened absorption liquid from which refrigerant vapor has been expelled is conducted from chamber 31 through conduit 35, an inner passage of liquid heat exchanger 24 and conduit 19 into the upper part of absorber 17.

The cooling unit 12 comprises two cooling elements 12a and 12b. Refrigerant vapor from generator 27 flows upward through rectifier 32 into condenser section 33a of the air-cooled condenser 33. Refrigerant liquefied in condenser section 33a flows into a U-shaped conduit 36 and thence through a conduit 37 into a liquid precooler 38.

The upper part of precooler 38 is connected by conduits 39 and 40 to the outer passage 14 of gas heat exchanger 15. Liquid refrigerant evaporates and diffuses into rich gas which circulates through precooler 38 with consequent absorption of heat from the liquid refrigerant. The precooled liquid flows from precooler 38 through conduit 10 into the upper part of cooling element 12a.

Refrigerant vapor not liquefied in condenser

section 33a flows from the right-hand leg of conduit 36 into a second condenser section 33b. Refrigerant liquefied in condenser section 33b also flows into conduit 36 and thence through conduit 37, precooler 38, and conduit 10 into cooling element 12a. Refrigerant not liquefied in condenser section 33b flows from the left-hand leg of conduit 36 into a third condenser section 33c. Refrigerant liquefied in condenser section 33c flows into the lower end of a vertical conduit 41 and thence through conduit 11 into the upper part of cooling element 12b. The conduits 10, 11, and 37 are formed to provide liquid traps whereby the condenser is sealed from cooling element 12b and precooler 38 and the latter is sealed from cooling element 12a.

The lower end of condenser section 33c is connected by conduit 41, vessel 42, and conduit 43 to the gas circuit, as at the gas heat exchanger 15, for example, so that any inert gas which may pass into the condenser can flow into the gas circuit. Refrigerant vapor not liquefied in the condenser flows through conduit 41 to displace inert gas in vessel 42 and force such inert gas through conduit 43 into the gas circuit. By forcing gas into the gas circuit in this manner, the total pressure in the system is raised whereby an adequate condensing pressure is obtained to insure condensation of refrigerant vapor in the condenser.

The cooling element 12a is shown in the form of a coil. This coil may be embedded in or otherwise suitably arranged in heat exchange relation with a shell, as shown in Figs. 4 and 5, to provide a plurality of freezing compartments adapted to receive trays for freezing water and other matter to be frozen. The cooling element 12b is arranged with a plurality of cooling heat transfer fins 44 whereby a relatively extensive surface is provided for cooling air in storage space 13.

The cooling elements 12a and 12b are connected in series relation with inert gas flowing downwardly therethrough in the presence of and in parallel flow with liquid which is introduced through conduits 10 and 11. The gas in the upper cooling element 12a, therefore, contains a lesser amount of refrigerant vapor than the gas in the lower cooling element 12b. The partial vapor pressure of refrigerant in the gas mixture formed in the cooling elements is a gradient, so that the evaporating temperature of liquid refrigerant in the cooling elements is also a gradient, the evaporating temperature of liquid being lower in the upper cooling element 12a which constitutes the freezing portion of the cooling unit.

In accordance with this invention, an auxiliary gas heat exchanger 45 is provided in the gas circuit whereby gas flowing from cooling element 12a flows in heat exchange relation with gas flowing toward cooling element 12a before such gas enters cooling element 12b. With this arrangement, heat is transferred from weak gas entering cooling element 12a to cool gas leaving the cooling element, thereby lowering the temperature of the gas entering the cooling element 12a. By cooling the weak gas in this manner before it enters the cooling element 12a the mean temperature of the upper cooling element is lowered, thereby improving the operation of this portion of the cooling unit and always insuring a sufficiently low temperature for freezing water and the like.

Due to gas heat exchanger 45, gas enters the lower cooling element 12b at a higher tempera-

ture than it would if entering directly from the upper cooling element 12a. With this arrangement, therefore, the mean temperature of the lower cooling element is increased. Thus, by lowering the mean temperature of the freezing portion of the cooling element and raising the mean temperature of the space cooling portion thereof, a wide temperature differential of the mean temperatures of the two portions is effected.

The condenser sections 33a, 33b, and 33c may be arranged and dimensioned in such a manner that liquid refrigerant is supplied to cooling element 12b through conduit 11 when the cooling air reaches a predetermined high temperature. If desired, a conduit forming a liquid seal or trap may be provided which connects the lower part of cooling element 12a and upper part of cooling element 12b, so that unevaporated liquid flows directly from the upper to the lower cooling element. Such a conduit connection 46 is indicated in dotted lines in Fig. 1. Instead of providing the conduit connection 46, unevaporated liquid may be permitted to flow from cooling element 12a into the auxiliary gas heat exchanger 45 and thence into the lower cooling element 12b. In such case evaporation of liquid takes place in gas heat exchanger 45, thereby exercising considerable influence in cooling weak gas flowing toward cooling element 12a.

The auxiliary gas heat exchanger 45 is at a higher temperature than cooling element 12a and at a lower temperature than gas heat exchanger 15. In order to prevent loss of cold the auxiliary gas heat exchanger may be insulated in any suitable manner. As shown in Fig. 1, the auxiliary gas heat exchanger 45 and precooler 38 are both embedded in insulation in a removable wall part 47 of the cabinet forming the thermally insulated storage space 13. The gas heat exchanger 15 is also embedded in insulation, particularly the upper cold portion thereof, to prevent loss of cold.

If desired, the auxiliary gas heat exchanger may be arranged in storage space 13 and employed as an additional space cooling element. Such a modification is shown in the system diagrammatically illustrated in Fig. 2. The parts of the system shown in Fig. 2 which are similar to parts in Fig. 1 are designated by the same reference numerals. In Fig. 2, the generator 27a is of a vertical type having a vapor-lift coil 48 disposed about the lower end of a flue 49 which extends through the generator. Enriched absorption liquid flowing from vessel 22 is raised by vapor-lift action from coil 48 through conduit 50 into the upper part of the generator. The weakened absorption liquid flows from the lower part of the generator through conduit 35, liquid heat exchanger 24, and vertical conduit 19 into the upper part of absorber 17.

In the system in Fig. 2 the air-cooled rectifier 32a is located above condenser section 33a. The condenser sections 33a, 33b, and 33c otherwise are arranged in a manner similar to that shown in Fig. 1. The conduit 11 in Fig. 2 is arranged in heat exchange relation with the outer passage of the horizontal gas heat exchanger 15a and through which passes the rich gas leaving cooling element 12b. The conduit 11 is connected to deliver liquid refrigerant to the upper part of auxiliary gas heat exchanger 45a which is located within storage space 13.

In this modification weak gas from absorber 17 flows through conduit 51, the outer passage of gas heat exchanger 15a, conduit 52, the inner

passage of auxiliary gas heat exchanger 45a, and conduit 21 into the upper part of cooling element 12a. The gas flows downwardly through cooling element 12a, the outer passage of auxiliary gas heat exchanger 45a, and cooling element 12b in parallel flow with liquid which enters through conduits 10 and 11. From cooling element 12b rich gas flows through the inner passage of gas heat exchanger 15a and conduit 16 to the lower part of absorber 17. The coldest part of gas heat exchanger 15a is also arranged within storage space 13 inasmuch as it may also be effectively employed for space cooling.

The particular arrangement of the condenser sections 33a, 33b, and 33c is particularly favorable for quickly producing below freezing temperatures in cooling element 12a when operation of the system is started after a shutdown or idle period. The refrigerant first liquefied in condenser section 33a flows into precooler 38 where it is precooled independently of the temperature of the space cooling element 12b. By precooling the liquid and lowering the temperature of the inert gas by the provision of the auxiliary gas heat exchanger, therefore, freezing temperatures are quickly produced by the upper cooling element 12a. By locating the auxiliary gas heat exchanger 45a in storage space 13 the heat transfer surface provided for cooling air is increased considerably. The surfaces of the auxiliary gas heat exchanger 45a as well as cooling element 12b may be maintained above the freezing temperature so that air in the storage space is kept at a relatively high humidity. This relatively high humidity is effected under these conditions because less water vapor is removed from air flowing in contact with the surfaces of the auxiliary gas heat exchanger 45a and lower cooling element 12b when these elements are maintained above rather than below the freezing temperature.

In Figs. 3 to 6 inclusive a practical embodiment of the invention is diagrammatically shown wherein the system in Fig. 2 is incorporated in a household refrigerator. The refrigerator includes a cabinet 54 having an inner metal shell 55 arranged to be supported within an outer metal shell 56 and insulated therefrom with any suitable insulating material 57. The inner metal shell 55 defines the storage space 13 into which access is afforded by a door 58 hinged to the front of the cabinet.

The rear wall of storage space 13 is provided with an opening into which fits the removable wall part 47, as shown most clearly in Figs. 4 and 6. The opening is substantially the width of storage space 13 so that cooling element 12a and 12b can readily be positioned in space 13 when the cover 47 is fitted into the opening. The gas heat exchanger 15a extends through the removable wall part 47 as also do the conduits connecting the cooling elements 12a and 12b and the condenser 33.

The lateral side walls of the outer shell 56 extend beyond the rear insulated wall of storage space 13 to provide a vertically extending compartment 59 in which parts of the system may be located. In Fig. 3 the condenser 33 and vessel 42 are arranged in the upper part of the compartment 59. The positions of the remaining parts of the system have not been shown in the drawings since their illustration is not necessary for an understanding of the invention. The remaining parts, however, may be positioned in any suitable manner in the lower part of com-

partment 59. The compartment 59 forms a flue through which air flows upwardly by natural draft over the surfaces of the condenser and absorber and cooling fins fixed thereto.

5 The upper cooling element 12a is formed as a looped coil having top and bottom parts shaped as shown in Fig. 6. This coil is arranged in heat exchange relation with a shell 60 which extends across the storage space 13 and is provided with a plurality of compartments 61 adapted to receive ice trays 62 and the like. The entire cooling unit may be provided with a front baffle plate (not shown) having suitable openings to permit insertion and removal of trays into and from the compartments 61. A suitable door (not shown) is preferably provided to close the freezing compartment 61.

20 The upper cooling element 12a is provided with a suitable insulating covering 63 which may be formed of semi-vulcanized porous rubber, such as, for example, sponge rubber or the like. The covering 63 may be provided with a plurality of short fins 64. Due to the insulating cover 63 and heat absorbing effect of the fins 64, the surfaces 25 of the freezing portion of the cooling unit may be maintained at or above the freezing temperature. By providing the fins 64 the insulating covering 63 may be made of less thickness than would otherwise be possible, because heat from 30 air in the storage space is transferred to these fins and distributed over the smooth outer surface of the covering 63 which may be made less porous than the other parts of the covering. With this construction the likelihood of frost forming 35 on the upper freezing portion of cooling unit 12 is avoided.

In order that the temperature of cooling element 12a will be maintained as low as possible at all times it is arranged at the top of storage space 13 in such a manner that the greater portion thereof is withdrawn from contact with air circulating in the space, thereby reducing the likelihood of frost forming on the surfaces thereof. While cooling element 12a is protected as 40 much as possible from air circulating in space 13, the lower cooling element 12b is arranged so that the surfaces thereof will effectively contact the circulating air. For this reason, the lower cooling element is made in the form of a rectangular coil extending across space 13 with cooling fins fixed to three sides thereof, as shown in Fig. 6. In order to improve the natural circulation of air which is induced by air coming in contact with the lower coil and fins 44, a 45 baffle plate 65 is positioned beneath the lower coil. The baffle plate 65 screens off the lower parts of fins 44 and the lower coil so that air cooled by flowing in contact with these surfaces does not immediately flow downward therefrom. 50 The baffle plate 65 is provided with a central opening 66 so that natural circulation of air takes place substantially in the manner indicated by the arrows in Fig. 5.

55 The inner and outer edges of baffle plate 65 are provided with flanges 67 to form a trough for collecting water that may drip from the lower cooling element 12b. The trough formed by baffle plate 65 is provided with a rear opening 68 whereby the water is discharged into a vessel 69 supported at the rear wall of storage space 13. The water in vessel 69 may be emptied at intervals or a drain conduit may be provided whereby the water automatically flows to a place outside the storage space 13.

70 75 While several embodiments of the invention

have been shown and described, it will be apparent to those skilled in the art that various modifications and changes may be made without departing from the spirit and scope of the invention, as pointed out in the following claims.

What is claimed is:

1. In an absorption refrigeration system having a plurality of evaporators at different levels and through which inert gas flows downward in series, means for supplying liquid refrigerant to said evaporators, a first heat exchanger between gas flowing to an upper evaporator and gas flowing from said upper evaporator to a lower evaporator, a second heat exchanger for gas flowing from said lower evaporator and gas flowing to said upper evaporator, and means to thermally insulate said first gas heat exchanger.

2. In combination with a refrigerator having a thermally insulated storage compartment and an absorption refrigeration system having a plurality of evaporators at different levels and through which inert gas flows downward in series, and means for supplying liquid refrigerant to said evaporators, a heat exchanger between gas flowing to an upper evaporator and gas flowing from said upper evaporator to a lower evaporator, said upper evaporator being thermally segregated from air in said compartment and said lower evaporator being arranged for cooling air in said compartment.

3. In combination with a refrigerator having a thermally insulated storage compartment and an absorption refrigeration system having a plurality of evaporators at different levels and through which inert gas flows downward in series, and means for supplying liquid refrigerant to said evaporators, a heat exchanger between gas flowing to an upper evaporator and gas flowing from said upper evaporator to a lower evaporator, and said upper evaporator being so constructed and arranged that it extends substantially from one side wall to the opposite side wall of said compartment just beneath the top wall of said compartment and is provided with a plurality of freezing chambers located alongside of each other.

4. In combination with a refrigerator having a thermally insulated storage compartment and an absorption refrigeration system having a plurality of evaporators at different levels and through which inert gas flows downward in series, and means for supplying liquid refrigerant to said evaporators, a heat exchanger between gas flowing to an upper evaporator and gas flowing from said upper evaporator to a lower evaporator, said upper evaporator being thermally segregated from said storage compartment and arranged in the upper part thereof and having an opening to permit the insertion and withdrawal of one or more ice trays, and both said heat exchanger and lower evaporator being arranged for cooling air in said compartment.

5. In combination with a refrigerator having a thermally insulated storage compartment and an absorption refrigeration system having a plurality of evaporators at different levels and through which inert gas flows downward in series, and means for supplying liquid refrigerant to said evaporators, a heat exchanger between gas flowing to an upper evaporator and gas flowing from said upper evaporator to a lower evaporator, said upper evaporator being thermally segregated from said storage compartment and located in the upper part thereof and having an opening to permit the insertion and withdrawal

of one or more ice trays, and said lower evaporator being in the form of a finned pipe coil for cooling air in said compartment.

6. In a refrigerator having a storage compartment and an absorption refrigeration system having a low temperature evaporator and a higher temperature evaporator to both of which liquid refrigerant is supplied for evaporation in the presence of an inert gas, a first pipe for conducting gas to said low temperature evaporator, and a second pipe for conducting all of the gas from said low temperature evaporator to said higher temperature evaporator, said first pipe being out of heat exchange relation with a major portion of said higher temperature evaporator and in heat exchange relation with said second pipe to exchange heat from gas flowing in said first pipe to said low temperature evaporator to gas flowing in said second pipe from said low temperature evaporator to said higher temperature evaporator, whereby the mean temperature of said low temperature evaporator is lowered and the mean temperature of said higher temperature evaporator is raised, and said low temperature evaporator being arranged to serve as a freezer and said higher temperature evaporator being arranged to cool air in said compartment.

7. In the art of refrigeration with the aid of a refrigeration system having first and second places of evaporation to which liquid refrigerant is supplied for evaporation therein in the presence of an inert gas, flowing inert gas to said first place of evaporation in a first path of flow out of heat exchange relation with a major portion of said second place of evaporation, flowing all of the inert gas in a second path of flow from said first place of evaporation to said second place of evaporation, and evaporating liquid in said second place of evaporation by heat abstracted from its surroundings, lowering the mean temperature of said first place of evaporation by abstracting heat from gas in said first path of flow and flowing to said first place of evaporation, and raising the mean temperature of said second place of evaporation by heating gas in said second path of flow and flowing from said first place of evaporation to said second place of evaporation.

8. In the art of refrigeration with the aid of a refrigeration system having two places of evaporation to which liquid refrigerant is supplied for evaporation therein in the presence of an inert gas, flowing inert gas to said first place of evaporation in a first path of flow out of heat exchange relation with a major portion of said second place of evaporation, flowing all of the gas in a second path of flow from said first place of evaporation to said second place of evaporation, and evaporating liquid refrigerant in said second place of evaporation by heat abstracted from its surroundings, lowering the mean temperature of said first place of evaporation by abstracting heat from gas in said first path of flow and flowing to said first place of evaporation, and raising the mean temperature of said second place of evaporation by utilizing said abstracted heat to heat gas in said second path of flow and flowing from said first place of evaporation to said second place of evaporation.

9. In a refrigerator having a storage compartment and an absorption refrigeration system having first and second evaporators through which inert gas flows downward in series and to which

liquid refrigerant is supplied for evaporation therein in the presence of said gas, a first pipe for conducting gas to said first evaporator, a second pipe for conducting gas from said first evaporator to said second evaporator, said first pipe being out of heat exchange relation with a major portion of said second evaporator and in heat exchange relation with said second pipe to exchange heat from gas flowing in said first pipe to gas flowing in said second pipe from said first evaporator to said second evaporator, whereby the mean temperature of said first evaporator is lowered and the mean temperature of said second evaporator is raised, and said second evaporator being arranged to cool air in said compartment.

10. In the art of refrigeration with the aid of an absorption refrigeration system having first and second evaporators to which liquid refrigerant is supplied for evaporation in the presence of an inert gas, flowing inert gas in a first path of flow out of heat exchange relation with a major portion of said second evaporator, flowing gas from said first path of flow to an upper part of said first evaporator for downward flow therein, flowing gas in a second path of flow from the lower part of said first evaporator to the upper part of said second evaporator for downward flow in the latter, and exchanging heat from gas in said first path of flow and flowing to said first evaporator to gas in said second path of flow and flowing from said first evaporator to said second evaporator.

11. In a refrigerator having a storage compartment and an absorption refrigeration system having a gas circuit including an absorber and first and second evaporators to which liquid refrigerant is conducted for evaporation therein in the presence of an inert gas, a first pipe for conducting inert gas from said absorber to said first evaporator, a second pipe for conducting gas from said first evaporator to said second evaporator, and a third pipe for conducting gas from said second evaporator to said absorber, said third pipe being in heat exchange relation with said first pipe through which gas flows to said first evaporator, said first pipe being out of heat exchange relation with a major portion of said second evaporator, said second pipe being in heat exchange relation with said first pipe at a region through which inert gas flows to said first evaporator after flowing in heat exchange relation with gas in said third pipe, and said second evaporator being arranged to cool air in said compartment.

12. In combination with a refrigerator having a thermally insulated storage compartment and an absorption refrigeration system having upper and lower evaporators to which liquid refrigerant is supplied for evaporation in the presence of an inert gas, a heat exchanger between gas flowing to said upper evaporator and gas flowing from said upper evaporator to said lower evaporator, said upper evaporator being thermally segregated from said compartment and located in the upper part thereof and having an opening to permit the insertion and withdrawal of one or more ice trays, said lower evaporator including a pipe coil having a relatively extensive heat transfer surface for cooling air in said compartment, and a baffle plate in said compartment below said lower evaporator, said plate having a central opening and being of such shape and size that circulation of air takes place upwardly adjacent the side walls of said compartment and downwardly through said opening.
13. In a refrigerator as set forth in claim 12, a trough associated with said baffle plate for collecting water dripping from said lower evaporator.
14. A refrigerator comprising a cabinet having a storage compartment, the storage compartment being open at the front of the cabinet, absorption refrigeration apparatus containing inert gas in the presence of which liquid refrigerant evaporates, said apparatus including low temperature and high temperature evaporators, said high temperature evaporator being arranged to abstract heat from the storage compartment and said low temperature evaporator being disposed at a higher level than said high temperature evaporator and located in the upper part of the storage compartment, said low temperature evaporator having a plurality of side walls forming a freezing receptacle for freezing ice and the like, structure including said low temperature evaporator being so arranged that circulation of air is effected in the compartment in such a manner that a major portion of the circulating air flows in a path avoiding two or more of the exposed exterior side walls of said low temperature evaporator with the major portion of the air cooling being effected by said high temperature evaporator, and a door for the cabinet opening for inserting and removing food products and the like into and from the storage compartment and also affording access to the freezing receptacle formed by said low temperature evaporator.
